UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,704, dated October 17, 1899.

Application filed September 23, 1899. Serial No. 731,497. Term of patent 14 years.

To all whom it may concern:

Be it known that I, JEREMIAH A. SCRIVEN, a citizen of the United States, residing in the city of New York, borough of Manhattan, in the county and State of New York, and whose postoffice address is No. 18 East Fifteenth street, have invented and produced a new and original Design for Bifurcated Nether Garments, of which the following is a specification.

The characteristic feature of my design consists in an insertion or panel let into the rear of the garment and extending laterally substantially from side to side of the garment and from substantially the upper end of the garment to a line extending transversely across the tubular members and below the crotch portion thereof.

In the accompanying drawings, Figure 1 is a rear view of a bifurcated nether garment embodying my design. Fig. 2 is a side view of the same.

Referring to the drawings, A indicates the body portion of the garment, from which extend tubular members B. Let into the rear of the garment is a panel or insertion C, which extends laterally substantially from side a to side a of the garment. The panel C likewise extends from substantially the upper end of the garment or from the band b to a line c, extending transversely across the tubular members D a short distance below the crotch of the garment. The ribs or wales d of the insertion C are shown running in a direction which is transverse to the length of the garment.
